UNITED STATES PATENT OFFICE

101,885

DESIGN FOR A ROAD MARKER FOR PUBLIC HIGHWAYS

Vincent Pellicone, Hollywood, Calif.

Application August 1, 1936, Serial No. 64,236

Term of patent 14 years

To all whom it may concern:

Be it known that I, Vincent Pellicone, a citizen of the United States, residing in Hollywood, in the county of Los Angeles and State of California, have invented a new, original, and ornamental Design for a Road Marker for Public Highways, of which the following is a specification, reference being had to the accompanying drawing, forming part thereof:

Figure 1 is a perspective view of a road marker for public highways, showing my design.

Figure 2 is a front elevation.

I claim:

The ornamental design for a road marker for public highways substantially as shown.

VINCENT PELLICONE.
